UNITED STATES PATENT OFFICE.

HARRY WADE, OF INDIANAPOLIS, INDIANA.

DESIGN FOR AN EMBLEM.

Application filed July 12, 1924. Serial No. 10,136. Term of patent 3½ years.

To all whom it may concern:

Be it known that I, HARRY WADE, a citizen of the United States, residing at Indianapolis, in the county of Marion and State of Indiana, have invented a new, original, and ornamental Design for Emblem, of which the following is a specification, reference being had to the accompanying drawings, forming a part thereof.

In the drawings Fig. 1 is a face view of an emblem showing my design, and Fig. 2 is an exaggerated edge view thereof.

I claim:—

The ornamental design for emblem as shown.

In witness whereof, I have hereunto set my hand at Indianapolis, Indiana, this 1st day of July, A. D., one thousand nine hundred and twenty four.

HARRY WADE.
